UNITED STATES PATENT OFFICE.

SAMUEL C. KENAGA, OF CHICAGO, ILLINOIS.

CORN-HARVESTER.

SPECIFICATION forming part of Letters Patent No. 447,465, dated March 3, 1891.

Application filed July 12, 1889. Serial No. 817,802. (No model.)

To all whom it may concern:

Be it known that I, SAMUEL C. KENAGA, of Chicago, in the county of Cook and State of Illinois, have invented certain new and useful Improvements in Corn-Harvesters; and I do hereby declare that the following is a full, clear, and exact description thereof, reference being had to the accompanying drawings, and to the letters of reference marked thereon, which form a part of this specification.

This invention relates to improvements in that class of corn-harvesters which have cutters or knives mounted on the frame of the machine and arranged to sever the standing corn by being drawn against the same in the forward movement of the machine—such, for instance, as is described and shown in Letters Patent of the United States No. 299,401, which were granted to me May 27, 1884.

The invention consists in the matters hereinafter described, and pointed out in the appended claims.

In the accompanying drawings, which illustrate a corn-harvester embodying my invention, Figure 1 is a plan view of the machine. Fig. 2 is a sectional elevation of the same, taken upon line 2 2 of Fig. 1. Fig. 3 is a sectional elevation taken upon line 3 3 of Fig. 1. Fig. 3^a is an enlarged detail view of the knife-supporting devices shown in Fig. 3. Fig. 3^b is a sectional view of the same, taken on line 3^b 3^b of Fig. 3^a. Fig. 3^c is a detail sectional view taken on line 3^c 3^c of Fig. 3. Fig. 4 is a detail section taken upon line 4 4 of Fig. 1. Fig. 5 is a detail perspective view of the devices for guiding the upper parts of the stalks. Fig. 6 is a cross-section taken on line 6 6 of Fig. 1. Fig. 7 is a detail section taken upon line 7 7 of Fig. 1. Fig. 7^a is a detail section of the rear bearing of the conveyer-shaft, showing the same in its changed position. Fig. 8 is a detail section of the knife, taken upon line 8 8 of Fig. 1. Fig. 9 is a detail section of the auxiliary cutter, taken upon line 9 9 of Fig. 2. Fig. 10 is a detail section of the forward part of the frame, taken upon line 10 10 of Fig. 1. Fig. 11 is a detail cross-section taken upon line 11 11 of Fig. 1. Fig. 11^a is a detail view of the rear knife-support. Fig. 12 is a side view of an alarm apparatus for indicating the point at which the accumulated stalks shall be discharged. Fig. 13

is a vertical section of the same, taken on line 13 13 of Fig. 12. Fig. 14 is a detail plan view of the thills of the machine and connected parts. Fig. 15 is a side view of the same. Fig. 16 illustrates a modified construction of the machine, wherein the thills are rigid with the machine-frame. Fig. 17 illustrates the machine when modified in shape to operate in harvesting cane or sorghum.

A machine as illustrated in the drawings is contrived to cut one row of corn at a time; and it consists, generally, of a rectangular frame supporting a platform to receive the cut corn and having attached to it at one side thereof a longitudinal exterior guide-piece, between which guide-piece and the adjacent side piece of the machine-frame is formed a guide-slot for the corn, within or across which the cutting-knife is placed. The machine is supported at its rear end by two wheels placed at either side thereof and at its front end by a third wheel, for which may be substituted, if preferred, two wheels, or rigidly-attached shafts or thills, as shown in said prior patent. In addition to the outer longitudinal guide above mentioned, suitably-arranged elevated guides or deflectors are provided upon the machine for throwing the tops of the standing corn forward and inward as the machine advances, so that when the stalks are encountered and cut by the knife the severed tops will fall into the receptacle. Means are also provided for conveying the butt-ends of the cut stalks laterally from the knife into the receptacle, the same consisting of a rotating spiral conveyer actuated from one of the supporting-wheels of the machine, as hereinafter more fully described.

The several parts of the machine above mentioned are constructed and operate substantially in the manner set forth in the application above referred to.

The frame of the machine, as herein shown, consists of two longitudinal side pieces A A', cross-pieces A² A², joining the side pieces at the front end of the frame, two horizontal cross-pieces A³ A⁴, which connect the two side pieces A A' at the rear end of the machine, and also a third longitudinal piece A⁵, arranged parallel with the frame-piece A at one side of the machine, and which supports and forms part of a longitudinal guide, indicated

as a whole by B, which is outside of the row of corn that is being cut.

B' and B² are rearwardly and upwardly inclined guide-pieces, and C, D, and D' are elevated guides or deflectors, arranged to bend and guide the standing cornstalks inwardly and forwardly over the frame of the machine as the stalks are cut in the forward movement thereof, as hereinafter more particularly described.

E is a tilting receptacle for the cut corn, said receptacle being located between the side pieces A A' of the frame, near the forward end of the latter. The receptacle E is arranged with its rear edge in advance of the cutting-knife, and is pivotally connected with the forward part of the frame, so as to enable its rear end to rise and fall in passing over stones or other obstructions upon the ground.

F is the cutting-knife, which is sustained upon the machine-frame in the manner hereinafter more particularly described, and extends across the space between the guide B and the longitudinal frame-piece A to a point inside of the exterior face of the latter, said knife being inwardly and upwardly inclined, in the manner and for the purpose set forth in the patent above referred to.

G is a guide-rod attached to the lower longitudinal piece A⁵ of the guide B and inclined inwardly in its forward part, so as to crowd the cornstalks together at their lower portions and to confine them adjacent to the frame-piece A, so that they will be readily cut off by the knife. Said guide-rod is located some-

what in advance of the forward end of the knife, and between the knife and the guide-rod is located a vertically-movable knife-support H, consisting of a flat and horizontally-arranged plate or frame, which is pivoted at its forward end to the machine-frame adjacent to the rear end of the guide-rod G, and extends beneath and is pivotally connected with the forward end of the knife. The inner edge of said knife-support H is arranged approximately in line with the rear end of the guide-rod G, and serves as a guide to retain the cornstalks adjacent to the frame-piece A until the latter are encountered by the knife.

I is a screw conveyer, which is mounted in suitable bearings upon the machine-frame, with its forward end adjacent to and in advance of the knife and which operates to convey inward to the receptacle E the butts of the cut corn as the same falls forward when severed by the knife. The said conveyer I is actuated by suitable intermediate driving-connections from a sprocket-wheel J upon one of the supporting-wheels K, which sus-

tain the rear part of the machine, as herein-after more fully set forth.

The front end of the machine is provided with thills L L, which are attached to a vertical forked frame L', carrying the forward supporting-wheel L². The frame L' is connected by a horizontal pivot l with a vertical

rod or shaft L³, with which the forward cross-bar A² of the frame is connected by means of a socket L⁴ on the frame which embraces the shaft L³. The cross-bar of the frame is adjustable vertically upon the shaft to admit of raising and lowering the forward end of the frame, the socket L⁴ being herein shown as adjustably sustained upon the shaft by means of a ring or collar l', held in place upon the shaft by pins l², which may be placed in either one of a series of holes l³ in said shaft.

L⁵ is a singletree, which is connected with the socket L⁴ by means of a link l¹, so that when the horse is drawing the machine the draft comes directly upon the main frame instead of upon the forked frame L'.

l⁵ l⁶ are brace-rods extending from the longitudinal side pieces A A' of the frame to the lower end of the shaft L³. Said brace-rods l⁵ l⁶ serve to rigidly connect the shaft L³ with the longitudinal frame-pieces, thereby maintaining said shaft in a vertical position. The brace-rods l⁵ are herein shown as secured to the shaft L³ by means of a collar l⁷, which surrounds the shaft, and to which the brace-rods are attached; but said brace-rods may be otherwise connected with the shaft, as found convenient or desirable. The horizontal pivot l enables the thills to swing freely in a vertical plane without disturbing the upright position of the shaft L³, while the shaft L³, turning in the socket L⁴, allows the shafts and wheel L² to be turned or swung horizontally in turning the machine.

The guide-pieces B' and B² are curved or rounded upon their upper and inner surfaces, so as to present no acute angles or edges upon which the ears of corn may become caught, and by which they may be detached from the stalks as the latter are pressed against and drawn over the said guide-pieces. The upper guide-piece B² is, furthermore, Fig. 3, desirably provided with an inner depending flat guide-surface or extension B³, which throws and holds outwardly-hanging ears on the stalks inwardly, so that the weight of the same will not tend to carry the stalks outwardly, and thus prevent the same from falling downwardly and forwardly into the receptacle. Such guide-surface, furthermore, prevents short stalks, or those which are slanted or inclined outwardly, from being thrown or cast through the space beneath the said guide B².

instead of being thrown inwardly, where they will be caught within the receptacle E. Said guide-pieces B' and B² are conveniently supported from the lower part of the machine-frame by means of a post or standard A⁶, bolted to the exterior frame-piece A⁵, and by another post A⁸, located upon the said frame-piece A⁵, in the manner illustrated. The forward upwardly and inwardly inclined guide-piece B' is attached at its forward end to the front end of the longitudinal frame-piece A⁵, and at its rear end to the post A⁸, which is

located upon the frame-piece A⁵ at a point in advance of the knife. The guide-piece B², which forms a continuation of the guide B', is arranged with its inner edge in a plane parallel with the longitudinal frame-pieces of the machine, and is supported at its forward end upon the post A⁸, and at its rear end upon horizontal cross-pieces A⁹ and A¹⁰, sustained upon the posts or standards A⁶ A⁷, short arms or braces a' a² serving to connect the said guide with the cross-pieces A¹⁰ and A⁹, in the manner illustrated. An oblique brace A¹³ extends from the cross-piece A⁴ to the cross-piece A¹⁰.

15 The guide or deflector C is preferably curved inwardly or backwardly in its middle part, and consists of a metal rod c, to which is attached an upwardly and outwardly flaring or curved piece c', of sheet metal, which 20 serves to prevent the ears of corn which rub or scrape over the said deflector from catching thereon, and thereby becoming detached from the stalks. Said deflector is held in place by means of a T-head c⁴, which has sliding engagement with a longitudinal slot b in the guide B², the opposite end of the deflector being supported by means of a slotted arm c³, which engages the guide-rod D in such manner as to sustain the end of the deflector from 25 vertical movement, while allowing the deflector to be easily adjusted backward and forward upon the machine.

To enable the deflector C to be easily moved by the driver, an actuating rod or bar C' is attached to the same, said rod having a handle c² at its rear end to be grasped by the driver. The bar C' is attached to the end of the bar c of the deflector at a point adjacent to the guide B², and an inclined brace-rod c⁵ 30 is preferably attached to the bar and to the rear surface of the deflector in the manner illustrated to strengthen the connection between the parts. Said bar C' is engaged with a guide-plate c⁶, attached to the rear end of the guide B², said bar being provided with a series of notches c⁷, either of which may be engaged with the guide-plate c⁶ to hold the deflector C from movement after it has been placed in the desired position. By the use of the 35 bar C' the deflector may be easily moved and the same secured in its shifted position without the driver leaving his seat. The slotted arm c³ is made of considerable length to allow the same to slide freely on the inclined 40 guide-bar D, this construction or some equivalent one obviously being required by reason of the inclination of the said guide-bar D with reference to the path of the deflector C when the same is moved. The said guide-rod 45 D is attached at its rear end to the upper transverse bar or frame-piece A¹⁰, which connects the frame-standards A⁶ A⁷, and at its forward end is attached to the exterior longitudinal frame-piece A' at a point near the 50 front end of the frame, said guide-rod being inclined downwardly and forwardly in such manner as to aid in guiding the tops of the

stalks as they fall forward into the receptacle. The upper guide-rod D' is located somewhat above the guide-rod D, and is intended for 70 supporting and guiding the upper ends of the stalks which project above the guide-rod D. Said guide-rod D' is inclined downwardly and forwardly from a point opposite the deflector C, and is attached at its rear end to the cross-piece A¹⁰ and at its forward end to a standard A¹¹, which rises from the longitudinal frame-piece A' in the manner illustrated. The upper end of said standard A¹¹ is desirably provided with a guide-ring a for the 80 reins, said guide-ring being so located as to hold the reins outside of the guides D and D', and clear of the falling corn, the frame-standard A¹¹ for this purpose being shown as bent outwardly in the manner illustrated. The 85 lower guide-rod D is preferably attached to the standard A¹¹ at its point of crossing the same, by which said rod is additionally supported in the manner illustrated.

The receptacle E is more clearly shown in 90 Fig. 4, and consists of a bottom e, which is curved upwardly at its front end, and two side pieces e' e'. The receptacle is connected at its front end with the machine-frame by means of a pivotal or hinged joint e², allowing the rear end of the receptacle to rise and fall. In the particular construction illustrated the front edge of the receptacle is connected by hinges e² e² with the transverse frame-piece A¹², which extends between and 100 is attached at its ends to the longitudinal frame-pieces A A' near the forward ends of the latter. The receptacle is sustained at its rear end from the frame by means of chains E' E', Figs. 2 and 4, the chains being attached 105 at their upper ends to the longitudinal frame-pieces A and A' and at their lower ends to the receptacle near the bottom of the latter. Said chains sustain the rear end of the receptacle free from the ground in the usual 110 operation of the machine while permitting the same to rise bodily and pass over obstructions, such as stones and lumps of earth. The said receptacle E is adapted to receive and hold the cornstalks severed by the knife and 115 thrown within the receptacle by the action of the deflector C, the several guides B', B², D, and D', and the conveyer I.

Devices are provided for discharging the 120 cut stalks which accumulate in the receptacle at desired times, the same being constructed as follows: At the rear end of the receptacle E is located a separate tail-piece or dropping extension E², which is hinged to the rear edge of the receptacle, so that its rear end 125 may be raised and lowered. At the forward part of the receptacle is located a tilting section E³, hinged at its rear to the receptacle in the forward part of the latter and extending past or forward of the front edge of the receptacle and adapted to swing upwardly and 130 backwardly at its forward end when the same is lifted. The dropping extension E² is connected with the swinging section E³ in such

manner that when the said section E³ is at the lower limit of its movement the dropping extension will be sustained free from the ground and in alignment with the bottom of the receptacle or a little above the same. The connection between the parts is so devised that when the forward end of the tilting section is lifted the dropping extension is allowed to fall into contact with the ground, or nearly so, these two parts operating to secure the discharge of the accumulated stalks within the receptacle by the falling of the dropping extension which allows the butts of the stalks to rest upon the ground, and by the lifting of the tilting section which forces the upper ends of the stalks rearwardly while at the same time throwing the stalks into an inclined position calculated to facilitate their discharge from the receptacle. The dropping extension E² and swinging section E³ are operated to discharge the bundle by the driver through the medium of any suitable connecting device, actuated through the medium of a handle or foot-piece located in position convenient to be operated by the driver, one simple and convenient form of which is herein shown.

The devices for connecting the dropping extension with the tilting section herein shown are made as follows: E⁴ is a rigid upwardly-extending arm attached to the dropping extension E², and so arranged that an approximately horizontal movement of the upper end of the arm will swing the dropping extension about its pivot. E⁵ is a rod attached to the upper end of the arm E⁴, and extending forward toward the tilting section E³, and E⁶ is another rod attached to the upper or forward end of the tilting section and connected with the rod E⁵. If the rods E⁵ and E⁶ are rigidly connected with each other, the dropping extension E² will be sustained thereby in its elevated position when the tilting section E³ is at the downward limit of its movement, and when said tilting section is lifted or swung backward the dropping extension will be depressed. Inasmuch, however, as the said dropping extension is likely to strike and be lifted by obstructions upon the ground at a time when it is thrown downwardly by the lifting of the tilting section, a yielding or sliding joint is made between the rods E⁵ and E⁶, so constructed that said rods may slide upon each other with the effect of shortening the connection in case the dropping extension is thrown forcibly upward at a time when the tilting section is lifted, this construction obviously affording safety from breakage or injury to the parts at such times. A further important advantage gained by this construction is that it enables the tilting section to be lifted or thrown back after the dropping section has struck the ground any distance necessary to insure the discharge of the stalks.

Any convenient form of sliding connection between the rods E⁵ and E⁶ may be employed for the purpose stated. As herein shown,

two metal blocks or clips e³ e³ are rigidly secured to the rod E⁵, and are provided with bearing-apertures, in which the rod E⁶ is adapted to slide, and said rod E⁶ is provided at its rear end with a head e⁴, which strikes the rearmost of the clips e³, so as to limit the relative movement of the rods and sustain the dropping extension above the ground in the ordinary operation of the machine. In case, however, the dropping extension encounters an obstruction and is lifted thereby at the time the tilting section E³ is thrown upward, the rod E⁶ slides in the clips e³ e³, and thus allows the dropping extension to freely rise. It will of course be seen that any kind of a connection between the tilting section and the dropping extension adapted to be shortened or contracted in the manner described, or which is flexible to allow its ends to be brought toward each other, may be employed to produce the desired result in place of the sliding rods described. A chain or flexible connection is not as desirable as the said rods, however, because the same would be liable to become entangled with the stalks in the operation of the machine.

As a convenient means of operating the tilting section and dropping extension from the driver's seat, a rod E⁷ is attached to the forward part of the tilting section and reaches upwardly and rearwardly to a point within reach of the driver, who sits at the rear end of the machine, said rod being provided with a handle e⁸, sustained at its rear end by passing through a guide-aperture in a guide-arm or standard e⁶, attached to one of the rear frame-standards A⁷. When the tilting section is lifted by drawing upwardly and rearwardly upon the rod E⁷, the dropping extension will obviously be actuated through its connection with the said tilting section.

The tilting section E³ is provided near its forward end with a transversely-arranged row of points or teeth E⁸, which extend upwardly from the surface of the tilting section and are herein shown as formed upon a plate secured to the same in the manner illustrated. The end portion E⁹ of the tilting section outside or in front of the points or teeth E⁸ is curved upwardly and forwardly or made convex upon its upper surface, in the manner illustrated, Fig. 4, and said part E⁹ bears such relation to the teeth E⁸ that when the tilting section is at the lower limit of its movement the stalks thrown or resting over the forward end of the tilting section will rest upon and be engaged by the said teeth, and when the tilting section is thrown upwardly and rearwardly the curved part E⁹ will be brought above the teeth and into such position as to sustain the stalks free from the said teeth, as clearly shown in dotted lines in said Fig. 4. The object of the teeth E⁸ is to hold the stalks from slipping backward from the receptacle until it is desired to discharge the stalks therefrom and also to thrust backwardly the stalks in the lifting of the tilting section, so as to prevent

the latter from merely sliding backward beneath the stalks at such time. The object of the convex surface E^9 is to lift the stalks free from the teeth after the tilting section has 5 been raised to a considerable distance, the stalks resting upon and sliding freely over said convex surface as they are drawn backwardly by the contact of their butts with the ground.

10 e^7 is a spring which is interposed between the forward part of the tilting section E^3 and the receptacle E , to take the weight of the said forward part of the tilting section when the latter is allowed to fall, said spring serving to prevent forcible striking or hammering of the tilting section against the receptacle at such time. In the particular construction illustrated the spring e^7 is of leaf form and secured at one end to the under surface 20 of the tilting section E^3 and rests at its free end against the bottom of the receptacle.

In order to enable the receptacle to be easily adapted for handling stalks of different lengths, the tilting section E^3 is made 25 bodily adjustable longitudinally with relation to the machine-frame, it only being necessary for this purpose to shift the point at which the tilting section is hinged to the receptacle backward or forward to bring the 30 tilting section in the desired place. It will of course be seen that in the handling of short stalks it is necessary to locate the tilting section farther to the rear, so that it will properly act upon the upper ends of the stalks as 35 it is lifted, while in cutting longer corn the tilting section must be placed farther forward, in order that the tops of the stalks may not project so far over the front end of the tilting section as to prevent the latter from 40 properly discharging the stalks. As a convenient way of shifting the point at which the tilting section is hinged to the receptacle, the hinges $e^8 e^8$ are bolted to the bottom of the receptacle and two or more sets of bolt-holes e^{80} are provided at different points in 45 the bottom of the receptacle, through either of which the bolts for securing the hinges may be inserted. When the tilting section is bodily shifted in the manner described, it is 50 obviously necessary to change the length of the connections uniting said tilting section with the dropping extension E^2 , and this may be conveniently done in the construction illustrated by shifting the position of one or 55 both of the blocks or clamps $e^3 e^8$ upon the rod E^5 . The actuating-rod E^7 may be also so constructed that its length may be changed to correspond with the location of the tilting section, the rod for this purpose being shown 60 as made in two parts arranged to overlap and joined by two clamp-plates e^9 , clamped to the parts of the rod by a central bolt.

65 E^{10} , Figs. 1, 2, and 6, is a flat upright shield extending longitudinally of the frame at the side of the receptacle E remote from the cutting-knife F . Said shield is herein shown as made of sheet metal and attached to the outer

face of the frame-piece A' ; but it may be otherwise constructed and secured to the frame as found convenient or desirable. Said shield 70 preferably extends from a point opposite the front of the receptacle to a point at the rear of the axle of the supporting-wheel K . The forward part of said shield serves to prevent the upper parts of the stalks and the blades 75 thereon from projecting outside of or beyond the side of the machine and retains the same within the receptacle. The rear part of the shield prevents down or bent stalks carried inwardly by the conveyer from being thrust 80 or falling into contact with the wheel K and becoming entangled therein. Said shield also serves to break the force of the wind and to prevent the same from displacing the stalks as the latter fall into the receptacle. 85

The cutting-knife F is provided at its outer edge and rear end with an upwardly-extending flange F' , which serves to support the ends of the cut stalks; or, in other words, to prevent the same from slipping rearwardly 90 or outwardly over or past the knife. Said cut ends of the stalks rest on the knife, which is made of considerable breadth for this purpose, and are retained by the said flange until, by the dropping of the upper ends of the 95 stalks, the butt-ends fall upon the conveyer I , and are thereby lifted from the knife, after which they are moved laterally away from over the knife by the conveyer and allowed to fall upon the rear part of the receptacle. 100

In order to afford ample support for the butts of the cut stalks, the rear end of the knife F is made of considerable width and is extended inwardly, giving the knife approximately an L shape, the cutting-edge f 105 having an inward or concave curve, as shown, and having its cutting-edge more nearly transverse to the direction of motion of the machine at its rear than at its forward part. That part of the flange F' which is located 110 at the rear of the end of the knife is arranged nearly at right angles to the direction of motion of the machine, so as to catch and hold the cut ends of the stalks as the latter slide over the knife after having been severed, this 115 part of the flange, however, being inclined to some extent inwardly and toward the rear of the machine, so as to allow the butts to escape freely from the same as said butts are carried inwardly, or toward the receptacle, by 120 the action of the spiral conveyer.

As illustrated in said Letters Patent herein-before referred to, the cutting-knife is shown as immovably attached to the frame, so that the stalks are always severed thereby the 125 same distance from the ground. It is sometimes found necessary or desirable to cut the corn at a higher or lower point, as may be required, for the proper operation of the knife or in view of the kind of corn being 130 cut or its condition. For the purpose mentioned I have made the knife vertically adjustable upon the machine-frame, and I have further provided at the rear end of the knife

a spring or yielding support adapted to allow some degree of vertical movement or vibration in the knife when in operation. As a further improvement I so sustain the 5 knife that it is at all times free to rise at either end or bodily, whereby its action in cutting is found to be greatly improved. The forward end of the knife is connected and movable vertically with the knife-support H, 10 and both of these parts are adjustably sustained from the machine-frame by a sliding connection limiting the downward movement of the knife-support and the front end of the knife, but allowing the same to rise freely in 15 cutting, thereby preventing the knife from binding on the cut stubs. Furthermore, the construction described allows the parts to rise freely in case the knife-support, which extends under the forward end of the knife, 20 strikes any obstacle upon the ground.

In the particular construction illustrated, Figs. 1, 3, and 6, a curved knife-supporting bar H' is bolted to the top of the knife-support H and extends upwardly therefrom 25 through a guide H², attached to the longitudinal frame-piece A⁵. Said bar H' is adapted to slide freely through the guide H² and is preferably curved to avoid the necessity of elongating the slot in the guide or of making 30 a hinged connection between the bar and the knife-support. At the upper end of the bar H', above the guide H², is secured a stop or projection h, adapted to strike the top of the guide, and thereby limit the downward movement 35 of the knife and the knife-support. Said stop h is adapted for adjustable connection with the bar H', so that the downward movement of the knife and the knife-support may be limited, as desired. As herein shown, the stop 40 h consists of a metal block, which is attached to the bar H' by means of a bolt passing through the block and through one of the series of bolt-apertures in the bar in the manner illustrated. The knife is pivotally connected at its front end both with the knife-support H and the supporting-bar H' preferably by means of a vertically-arranged lug f' upon the knife, which is pivoted to the bar H' near the lower end of the latter. Said lug f' 45 is herein shown as formed upon a plate or casting, which is bolted to the forward end of the knife in the manner illustrated. The guide H² is herein shown as formed by means of two pieces, Fig. 3^b, of metal bent, bolted to the frame-piece A⁵, and extending inwardly therefrom to form two parallel horizontal lugs or 50 projections, through which passes the bar H'. At its rear end the knife F is supported by devices constructed as follows: F² is an up- 55 right metal rod, which is herein shown as supported at its upper end on an arm or bracket f², attached to the transverse frame-piece A⁹ and at its lower end to a horizontal transversely-arranged arm f³, which extends outwardly to the frame-standard A⁶ and is secured to the latter. The said rod F² is located 60 near the rear end of the knife F in the man-

ner clearly shown in Figs. 1 and 11. f⁴ f⁴ are two slotted arms attached to the flange F' of the knife and engaging the rod F², and F³ is 70 a spiral spring placed around said rod between the lowermost of the arms f⁴ and the arm f³, which is attached to the lower end of the rod. The slotted arms f⁴ f⁴ are adapted to slide freely on the rod F², thereby allowing a vertical movement of the rear end of the knife, 75 while the spring F³ yieldingly supports said rear end of the knife and allows a small extent of downward play therein during the operation of cutting the stalks. The rear end 80 of the knife is of course free to rise by the sliding of the arms f⁴ f⁴ on the rod F², this being the way in which it moves to the greatest extent in the operation of cutting, because the knife tends to rise as it passes over the 85 stubs of the obliquely - severed stalks. The engagement of the two slotted arms f⁴ f⁴ with said rod F² obviously prevents the knife from lateral movement or from twisting, while allowing the slight vertical movement desirable 90 in the operation of the knife.

The vertical adjustment of the knife to enable it to cut the stalks at a greater or less distance from the ground is accomplished by making the rod F² and arm f³, which is attached to the lower end of the same, vertically adjustable upon the machine-frame, and also by providing vertical adjustment for the stop h on the knife-supporting bar H' at the forward end of the knife, in the manner here- 100 inbefore described.

The adjustable connection of the bar F² and arm f³ with the frame is herein shown as formed as follows: The outer end of the arm f³ is attached by a bolt f⁵ to the frame-standard A⁶, and in said frame-standard are formed several bolt-apertures, within either of which the bolt f⁵ may be placed. Said rod F² is provided in its upper part with a series of holes, in either of which may be placed a pin 105 f⁶, which engages the arm f², and thereby sustains the rod F² in position vertically.

The knife-support H is herein shown as made of sheet metal and bent or curved upwardly at its rear end beneath the forward 115 end of the knife to enable it to ride smoothly upon the ground or over any obstruction which it may strike either in going forward or in backing the machine. The hinged connection between the forward end of the said 120 knife-support and the frame is conveniently formed by bending inwardly the rear end of the rod G at right angles, and bending around the transverse part of said rod the end of the said knife-support, so as to form a hinged 125 joint.

As herein illustrated and preferably constructed, the screw conveyer I is mounted at its forward end in a bearing i, which is supported upon the longitudinal frame-piece A 130 somewhat in advance of the cutting-knife. Said bearing i is made vertically adjustable with reference to the frame in order to enable the conveyer to be adjusted vertically when

desired. The devices for adjustably supporting said bearing upon the frame, which are herein shown, consist of a standard i' , which is bolted to the frame-piece A and enters and slides within a depending tubular part i^2 on the bearing i . A pin i^3 , inserted through the said tubular part i^2 and engaging one of the series of holes in the standard i' , serves to sustain the bearing in a desired vertical position.

5 A guide-rod G' extends from the bearing i forwardly to a point near the front end of the frame, where it is attached to the latter, said rod G' being arranged above the frame-piece A and serving to guide the stalks and prevent them from catching in the conveyer-support as they move backwardly toward the knife. The conveyer I extends across the machine rearwardly and inwardly from the bearing i , so that the butt-ends of the 10 cut stalks will fall across its forward end and will be carried by the spiral flange therein inwardly until they are no longer supported by the conveyer, when they drop into the receptacle. A shield or deflector I' , 15 preferably made conical and of sheet metal, is attached to the conveyer-shaft near or at its rear end, the same being designed to prevent the stalks from being carried backward and deposited too far at the rear, the butts of 20 the stalks striking the said shield or deflector in case they are carried backwardly far enough to encounter the same. At its rear end the conveyer is sustained in a bearing I^2 , which is attached to the top of the transverse frame-piece A³. This bearing is capable of vertical adjustment to change the distance of the conveyer from the ground, said bearing being adapted for removal from the frame-piece A³ and being adapted to be attached beneath 25 said frame-piece A³ in case it is desired to lower the spiral conveyer. Fig. 7^a shows the bearing in its changed position. Said bearing I^2 is herein shown as provided with an arm I^6 , by which it is attached to the frame-piece.

30 To facilitate the attachment of the bearing I^2 beneath the frame-piece A³, a casting a^3 , Fig. 7, the lower surface of which is fitted to the upper face of the arm I^6 , is secured to the frame-piece by the same bolt which holds the 35 said arm against the frame-piece.

The driving connections for actuating the conveyer-shaft are, as herein shown, constructed as follows: To the rear end of the conveyer-shaft is connected, by means of a 40 universal or gimbal joint i^4 , a shaft I^3 , to the rear end of which is secured a beveled pinion i^5 . I^4 is a horizontal transverse shaft located at the extreme rear end of the machine and mounted in suitable bearings i^7 i^7 upon the 45 machine-frame. The shaft I^3 is mounted at its rear end in a bearing i^6 , which is pivotally supported on the shaft I^4 in the manner illustrated, Fig. 7, thereby allowing the front end of the said shaft I^3 to be swung vertically when 50 the conveyer is moved up or down. The said shaft I^3 is desirably provided with a longitudinally-sliding joint, by which the shaft may

be lengthened or shortened when the bearing I^2 is raised or lowered. As herein shown, such joint is formed by a square end i^{10} on the shaft, which fits in a socket i^{11} in the member of the gimbal-joint with which the shaft is immediately connected. The shaft I^4 is provided at its outer end with a pinion I^5 , which is engaged with the gear-wheel J^3 , mounted upon a short shaft J^4 , upon which is fixed a sprocket-pinion J' , and the said gear-wheel is driven by means of a chain belt J^2 , trained over the said sprocket-pinion J' and the sprocket J upon the wheel K . A beveled gear-wheel i^8 , mounted upon the shaft I^4 , engages with and actuates the beveled pinion i^5 , upon the rear end of the shaft I^3 . Said shaft I^3 carries a crank-disk i^9 , by which is operated an auxiliary cutting-knife, arranged as hereinafter described.

I^5 is a transverse shield or plate extending from a point behind the rear end of the cutting-knife to a point at the rear of the rear end of the conveyer. Said plate I^5 serves as a guard to prevent the butts of stalks which may enter the space between the conical deflector and the rear flange of the knife from being carried rearwardly and becoming caught in the adjacent parts of the machine in the act of dumping the stalks, it being obvious that any stalks which rest across the conveyer with their tops on the tilting section E^3 at the moment the latter is lifted to discharge the stalks are liable to be thrust backwardly over said conveyer, unless the said shield is present, in which case their front ends slide forward over the tilting section as the latter is raised, while their rear ends are moved laterally by the conveyer until they drop therefrom. Said shield I^5 is herein shown as riveted to the arm or bracket I^6 , which sustains the bearing I^2 ; but it may be otherwise attached to or sustained on the machine frame.

The auxiliary cutter hereinbefore referred to is for the purpose of catching and cutting off any down or bent stalks which may so lie that the cutting-knife will not operate upon them, and which are therefore likely to pass under the knife in the forward movement of the machine. Such auxiliary cutter also cuts off any loose blades, vines, weeds, and other things which would otherwise be caught and accumulate beneath and at the rear of the knife. Any such down or bent stalks are likely to be thrown laterally, so as to bring their tops toward the conveyer or beneath the same, and are liable to be left unsevered by the main knife, owing to their downward and forward inclination. The said auxiliary knife is located at the rear of the cutting-knife and upon the longitudinal frame-piece A, which constitutes the inner guide for the stalks. The auxiliary knife thus located operates to sever the forwardly and inwardly bent stalks when the latter reach the space between the top of the said longitudinal frame-piece A and the rear end of the main cutting-knife,

which latter extends inwardly over the said longitudinal frame-piece some distance above the same. Said auxiliary cutter is made as follows: M is an upright stationary casting secured to the frame-piece A at the rear of the main knife parallel with the said frame-piece A and extending upwardly from the latter. Said casting M is provided with a central notch or recess having opposite parallel or nearly parallel cutting-edges m m, preferably formed by separate steel plates attached to the casting M at its upper and lower margins. To said casting M is pivoted an oscillating knife M', which is mounted on a pivot m', and which is provided with converging or angular cutting-edges, which operate in connection with the cutting-edges m m, with a shearing action in the manner of ordinary scissors or shears. The knife M' is provided with an arm m², to the end of which is pivoted by a pin m²⁰ a pitman M², which engages the crank-pin of a crank-disk i² upon the end of the shaft I¹. The rotary movement of said shaft gives an oscillatory movement to the knife M', by which anything drawn or carried into the spaces at the side of the knife and between the same and the cutting-edges m m is severed. The notch or opening in the plate M, within which the knife moves, is so located that stalks escaping the main knife F and passing beneath the same will be drawn against the said knife, the lower part of the plate being provided with an inclined guide-surface m³, which slants upwardly and rearwardly from the frame-piece A in such manner as to guide the stalks moving along said frame-piece upwardly and into the notch of the casting and in position to be acted upon by the knife.

40 The supporting-wheels K K of the machine are, as herein shown, mounted upon short studs or axles K' K', attached to plates K² K², which are adjustable vertically upon the frame-standards A⁶ A⁷, to give a desired vertical adjustment of the machine-frame with reference to the ground.

N is a seat for the driver, which is secured to the transverse frame-pieces A³ A⁴ at the rear of the machine, in the manner illustrated.

50 For the purpose of parting the corn in front of the horse a parting-guide L⁵ is provided, the same consisting of a curved or bent rod attached at its ends to the front of the thills and projecting forwardly and downwardly therefrom, as clearly shown in Figs. 14 and 15. The parting-guide thus constructed will obviously lift up as well as part any downwardly-bent stalks in the path of the machine. It is obviously not essential that the parting-guide should be double or joined to both thills in the manner described, inasmuch as in most cases it is sufficient to attach the guide to the thill nearest the row of corn being operated upon and to employ a single guide only, only 65 one parting-guide being necessary, except when the machine is passing between two close rows of corn. A parting-guide arranged

and operating in the manner described, furthermore, need not extend continuously from one thill to the other, but a separate guide 70 may be employed upon each thill with substantially the same result. The particular construction illustrated is usually, however, preferred as affording a simple and strong construction in the parting-guide.

75 As a further and separate improvement I locate upon the machine, below and approximately parallel with the thill at the side of the machine nearest the row being cut, a guide-rod O, which is attached at its forward 80 end to the parting-guide L⁵ and extends rearwardly to a point adjacent to the main frame of the machine. The guide O thus arranged serves to hold outwardly the fallen and other stalks which have been pressed out of the 85 path of the machine by the parting-guide L⁵ until the guides at the sides of the machine reach the pressed-out stalks, thereby preventing the same from falling inwardly beneath the thills and getting caught beneath the 90 frame of the machine or the wheels. Said guide O further acts as a brace for the parting-guide L⁵.

95 As shown in Figs. 14 and 15, the guide O is bent upwardly near its rear end and attached 100 to the thill itself. This construction, however, illustrates only one way of supporting a guide-rod of this kind, and it may be sustained in other ways, as found convenient or desirable, as for instance, the machine in 105 some instances may have only two wheels and rigid thills, and in such case the guide-rod O will conveniently be extended from the main part of the machine-frame forwardly to the parting-guide L⁵. A construction of this kind 110 is shown in Fig. 16, wherein the guide O is attached at its forward end to the parting-guide L⁵ and at its rear end to the main longitudinal frame-piece A near the forward end 115 of the machine.

116 In order to prevent any standing corn-stalks from entering between the wheel and the body of the machine at the side thereof opposite the knife, a guide-rod or fender L⁶ is desirably provided, said rod being attached 120 to the outer end of the wheel-axle and to the machine-frame at a point in advance of the wheel.

125 In Figs. 12 and 13 I have shown an automatic alarm device actuated by the turning 120 of one of the wheels of the machine and provided with a bell or gong which is sounded at equal intervals of space traveled by the machine, so as to indicate to the operator at what points the accumulated stalks must be dumped 125 in order to bring the piles of stalks in equidistant rows across the field. In the particular form thereof herein shown the said alarm device is constructed as follows: P is a metal base-plate of the apparatus, which is attached 130 to the machine-frame at a point adjacent to one of the main supporting-wheels K, said base-plate preferably being attached to one of the plates K², Fig. 11, to which the wheel-axles

K' are attached. Upon said plate P is pivoted a vertically-arranged actuating-lever P' , located adjacent to the wheel-hub and in position to be encountered by a stud k upon one 5 of the spokes of the wheel, as clearly shown in Fig. 12. The lever P' is provided with an arm P^2 , to which is connected a coil-spring P^3 , adapted to return the actuating-lever to its normal position after it has been moved 10 by the action of the stud k thereon. Q is a shaft mounted upon the plate P and having mounted thereon two ratchet-wheels $Q' Q^2$, a cam or wiper Q^3 , and a ratchet-wheel Q^4 . Said shaft Q is herein shown as made tubular or 15 hollow and mounted on a hollow stud or sleeve q , which is held in place upon the plate P by means of a bolt q' . The several cams and ratchet-wheels are desirably surrounded by means of a casing P^4 , attached to the upper 20 part of the plate P to protect said part from dust and dirt. The several ratchet-wheels and the cam are rigidly attached to and turn with the shaft Q. The ratchet-wheel Q^4 is merely for the purpose of preventing the 25 shaft from turning backwardly, and is engaged by a spring-pawl q^2 . R is a bell or gong which is acted on by a hammer R' , supported upon a bent lever R^2 , which is mounted on a pivot r . The end r' of said spring-arm 30 is held in the path of the cam or wiper Q^3 by means of a spring r^2 . Said parts are so arranged that said lever will be actuated by the cam and the hammer allowed to fall against the bell at each revolution of the shaft 35 Q. The gong R and lever R' are herein shown as mounted on the upper part of the casing P^4 . S is a pawl pivoted to the lever P' , engaging one of the ratchet-wheels $Q' Q^2$, and s' is a spring mounted on a stud attached to 40 said lever and provided with an arm acting upon said pawl S to hold the same in contact with the said ratchet-wheels. One of said ratchet-wheels Q' has fewer teeth than the other ratchet-wheel Q^2 , the wheel Q' , as herein 45 shown, having four teeth, while the wheel Q^2 has five teeth, and the pawl S is allowed to be shifted laterally by sliding on the pivot-stud s to engage either one or the other of said ratchet-wheels, as desired. The extent 50 of oscillatory movement of the lever P' is such as to carry the pawl over one tooth of the ratchet-wheel engaged therewith at each movement of the actuating-lever P' . It follows, therefore, that when the pawl S is engaged with the ratchet-wheel Q^2 the lever P' must be moved five times to accomplish the 55 turning of the shaft once, and when the said pawl is engaged with the ratchet-wheel Q' four movements of the actuating-arm are required to turn the shaft once. Inasmuch as the hammer R' is actuated once for each complete rotation of the shaft, it follows that when the pawl is acting on the ratchet-wheel Q^2 , having five teeth, the bell will be sounded 60 once for each five turns of the main supporting-wheels K of the machine, and when the pawl is engaged with the ratchet-wheel Q' ,

having four teeth, the bell will be sounded at each four revolutions of the supporting-wheel K. It will of course be understood that the ratchet-wheels $Q' Q^2$ may be provided with a greater or less number of teeth, in accordance with the distance apart at which it is desired to deposit the bundles of stalks, and that only one or more than two ratchet-wheels may be employed, as desired. When only one ratchet-wheel is used, the intervals between the action of the alarm-bell cannot be changed, and the employment of two or more of such ratchet-wheels affords the advantage of enabling the operator to adjust the alarm device so that it will act more or less frequently, as desired. The actuating-lever P' is so located with reference to the stud k that the stud will engage and move the lever both in turning 85 backward and forward, thereby preventing injury to the parts in case the wheel K is turned backward in backing the machine or turning the same around.

In Fig. 17 I have shown a machine containing the same general features of construction above described, but modified for use in cutting sorghum-cane, which is much taller than corn. To adapt the machine for use in sorghum the receptacle E is removed and a longer 95 and larger receptacle T is placed upon the front part of the frame and extends forward of the front end of the latter, the draft-connections being arranged to bring the horse farther forward, so as not to interfere with the 100 said receptacle. Said receptacle T is of trough shape, open at its front and rear ends and located in an inclined position, as shown, so that the tops of the cane resting therein may slide freely backwardly out of the receptacle 105 when the rear ends of the cane are dropped upon the ground. Said receptacle T is provided at the side of the machine opposite that at which the cutting-knife is placed with an upward extension t of its side wall for preventing the tops of the cane from being thrown over the same as they fall laterally 110 after being cut.

Devices for sustaining the butt-ends of the stalks and for dropping the same upon the ground for the purpose of discharging the cane are made as follows: U is a vertical shaft located at the side of the frame opposite the cutting-knife and having a horizontal arm U' , which may be either swung cross-wise of the frame in position to receive the butts thrown or carried inwardly by the conveyer T, or may be swung rearwardly parallel with and adjacent to the longitudinal frame-piece A' to allow the butts to drop upon 120 the ground. For actuating the shaft U to accomplish the shifting of the arm U' in the manner described, said rock-shaft is provided with a crank-arm u , connected by a pitman u' with a hand-lever U^2 , located within reach 125 of the driver. A support for the butts of the cane, constructed substantially in the same manner as above described, is shown in said prior patent, No. 299,401, and is not therefore 130

herein claimed as part of my invention. V is an auxiliary guide-rod attached to the frame-standard A⁷ at the side of the machine opposite the cutting-knife, extending upwardly and then downwardly and forwardly and attached to the side of the receptacle T and to the frame-piece A'. Said guide-rod V operates to guide the tops of the cane downwardly and forwardly as the cane is thrown inwardly over the machine at the time of being cut and to bring the same within the receptacle in an obvious manner.

I claim as my invention—

1. The combination, with the thill of a corn-harvester, of a downwardly and forwardly extending guide-rod or parting-guide, and a longitudinal guide-rod located below the thill, attached at its forward end to the said parting-guide, and extending rearwardly to a point adjacent to the front end of the machine, substantially as described.

2. The combination, with the frame of a corn-harvester and a cutting-knife thereon, of an elevated deflector for throwing the tops of the corn forward, said deflector being longitudinally adjustable upon the machine-frame, substantially as described.

3. The combination, with the frame of a corn-harvester and a cutting-knife thereon, of a deflector for throwing the tops of the corn forward, said deflector being longitudinally movable on the machine-frame, and a locking device for securing said deflector in place, substantially as described.

35 4. The combination, with the frame of a corn-harvester and a cutting-knife thereon, of a deflector for throwing the tops of the corn forward, said deflector being longitudinally movable on the machine-frame, and a bar for moving said deflector, attached to the deflector and extending rearwardly therefrom, substantially as described.

5. The combination, with the longitudinally-adjustable deflector C, having sliding connection with the machine-frame, of a bar connected with said deflector, said bar being provided with a series of notches, and a stationary stop or projection upon the frame adapted to engage either one of said notches, substantially as described.

6. The combination, with the frame of a corn-harvester and elevated lateral guides for the stalks thereon, of a longitudinally-adjustable deflector for throwing the tops of the corn forwardly, said deflector having sliding engagement with said guides, substantially as described.

7. The combination, with the frame of a corn-harvester, an elevated lateral guide B², running outside of the stalks to be cut, and an inclined lateral guide D, of a longitudinally-adjustable deflector for throwing the tops of the corn forwardly, said deflector having sliding engagement at one end with the said guide B² and being provided with a slotted arm, which is engaged with the said inclined guide, substantially as described.

8. The combination, with the lateral guide B², provided with a longitudinal guide-slot, of the deflector C, provided at one end with a T-head engaging said slot, and a guide for the opposite end of said deflector, substantially as described.

9. The combination, with the frame of a corn-harvester, a cutting-knife, and a receptacle for the cut corn, of a longitudinally-arranged elevated guide for bending the tops of the standing corn inward, said guide being curved or rounded on its upper and inner surface, a longitudinally-adjustable elevated deflector for throwing the tops of the corn forward, and a vertical guide-surface extending downwardly from said guide to a point below the ears on the standing stalks, substantially as described.

85 10. The combination, with the frame and cutting-knife of a corn-harvester, of a receptacle for the cut corn, a hinged dropping extension at the rear end of said receptacle, and means for actuating said dropping extension, embracing a support for the extension, which is contractible to allow the same to rise to pass over obstructions at times when it is lowered, said receptacle having vertically-movable connection with the frame, whereby the said receptacle may rise and the hinged extension may be bodily lifted to pass over obstructions, substantially as described.

11. The combination, with the frame and cutting-knife of a corn-harvester, of a receptacle for the cut corn, comprising a hinged rear part or dropping extension adapted to swing downwardly to discharge the stalks, and a separate tilting section at the forward part of the receptacle, the forward end of which section is constructed to swing upwardly and rearwardly, so as to thrust the cut stalks toward the rear of the machine, substantially as described.

12. The combination, with the frame and cutting-knife of a corn-harvester, of a receptacle for the cut corn, comprising a hinged dropping extension at the rear end of said receptacle and a separate tilting section at the forward part of said receptacle for thrusting backward the cut stalks, and a connection between the dropping extension and hinged section, by which the former will be lowered when the latter is elevated, substantially as described.

120 13. The combination, with a receptacle for cut corn, a dropping extension at the rear end thereof, and a tilting section at the forward end thereof, of a connection between said parts, which is contractible to allow the dropping extension to arise to pass over an obstruction in its path, substantially as described.

125 14. The combination, with the receptacle E, comprising a dropping extension E² and a tilting section E³, of a rigid arm upon the said dropping extension, rods connecting said arm with the tilting section, blocks or clips affording sliding connection between said rods, and

stops upon the rods adapted to engage the blocks or clips for limiting the extension of the rods, substantially as described.

15. The combination, with the frame and cutting-knife of a corn-harvester and a receptacle for the cut corn, comprising a dropping extension hinged at the rear end of said receptacle and a separate tilting section hinged to the forward end of the receptacle for thrusting rearwardly the cut stalks, said tilting section being connected with and constructed to actuate the dropping extension, of an actuating bar or rod connected with the said tilting section and extending to a point within reach of the driver, substantially as described.

16. The combination, with the frame and cutting-knife of a corn-harvester and a receptacle for the cut corn, of guides or deflectors for deflecting the corn-tops inwardly and forwardly over the receptacle, and a rotating spiral conveyer located at one side of the knife and provided with a shield or deflector at its rear end, substantially as described.

17. The combination, with the frame and cutting-knife of a corn-harvester and a receptacle for the cut corn, of guides or deflectors for deflecting the corn-tops inwardly and forwardly over the receptacle, and a rotating spiral conveyer located at one side of the knife, said conveyer being adjustable vertically on the machine-frame, substantially as described.

18. The combination, with the frame and cutting-knife of a corn-harvester and guides on the frame throwing the tops of the corn forwardly and inwardly, of a receptacle for the cut corn, consisting of a main part or body supported on the frame, and a tilting section to receive the tops of the corn, located at the front part of the receptacle and hinged at its rear end to said receptacle, so that its forward end may swing upwardly and rearwardly against the tops of the stalks to thrust the latter rearwardly out of the receptacle, substantially as described.

45. 19. The combination, with the frame of a corn-harvester, comprising a longitudinal frame-piece A, which forms a guide for the stalks, and a cutting-knife, of a rotating spiral conveyer located adjacent to the knife, and a support for the forward end of the conveyer, comprising a standard i' , attached to the frame-piece A, and a tube i^2 , engaging said standard, a bearing i , attached to the top of the tube, and a pin or other equivalent means for securing the tube from the movement on the standard, substantially as described.

20. The combination, with the frame of a corn-harvester, of a cutting-knife supported thereon, said knife having upwardly-yielding connection at each end with the machine-frame, and adjustable means for determining the lowermost position of the knife, substantially as described.

65. 21. The combination, with the frame of a corn-harvester, of a longitudinally-arranged

cutting-knife having an oblique cutting-edge and vertically-movable connection with the frame at its forward and rear ends by means allowing free upward movement of both ends thereof, and a spring applied to yieldingly sustain the rear end of the knife from downward movement, substantially as described.

22. The combination, with the frame of a corn-harvester, of a longitudinally-arranged cutting-knife supported on the frame, said knife having upwardly-yielding connection with the frame at both its front and rear ends, and an upwardly and forwardly inclined vertically-movable knife-support or guard connected with the front end of the knife, substantially as described.

23. The combination, with the frame of a corn-harvester, of a cutting-knife supported upon the frame, said knife having upwardly yielding connection with the frame at both ends, and an upwardly-yielding knife-support pivotally connected at its front end with the frame and connected with the forward end of the knife, substantially as described.

24. The combination, with the frame of a corn-harvester and a cutting-knife having upwardly-yielding connection with the machine-frame at both ends, of a swinging knife-support sustaining its forward end, an upright rod attached to the machine-frame and guiding the rear end of the knife, and a spring sustaining the rear end of the knife, substantially as described.

25. The combination, with the frame of a corn-harvester, of a cutting-knife thereon, having upwardly-yielding connection with the frame at both ends, a swinging knife-support H, said knife-support being pivoted at the forward end of the machine-frame and pivotally connected at its rear end with the forward end of the knife, and a stop for limiting the downward movement of the forward end of the knife and the knife-support, substantially as described.

26. The combination, with the machine-frame and a cutting-knife having vertically-movable connection at its rear end with the frame, of a knife-support hinged at its forward end to the machine-frame and pivoted at its rear end to the forward end of the knife, a rod or bar connected with the said knife-support and having sliding engagement with the machine-frame, and an adjustable stop upon said rod or bar for limiting the downward movement of the said knife-support and the forward end of the knife, substantially as described.

27. The combination, with the frame of a corn-harvester, of a cutting-knife provided with a rearwardly and inwardly inclined cutting-edge, which is inwardly curved at its rear part, said knife being provided with an upwardly-extending flange along its outer edge and across its rear end, substantially as described.

28. The combination, with the machine-

frame and a rearwardly and inwardly inclined cutting-knife sustained thereon and operating to sever the stalks by being drawn or carried against the same in the forward movement of the machine, of an auxiliary cutter arranged adjacent to the rear end of the main knife with its cutting-edge in a vertical plane for cutting off inwardly-bent and down stalks which escape the main knife, substantially as described.

29. The combination, with the frame and a cutting-knife of a corn-harvester, said frame being provided with a lower longitudinal inner guide for the corn, of an auxiliary cutter located above the said guide at a point adjacent to the rear end of the main knife, substantially as described.

30. The combination, with the frame and cutting-knife of a corn-harvester and a spiral conveyor thereon, of an auxiliary cutting-knife located adjacent to the rear of the main knife and adjacent to the conveyor for cutting off bent or down stalks which escape the main knife, substantially as described.

31. The combination, with the frame of a corn-harvester and a cutting-knife thereon, said frame being provided with a longitudinal frame-piece, which forms an inner guide for the corn and which extends beneath the rear end of the knife, of an auxiliary cutter attached to said longitudinal frame-piece near the rear end of the knife and extending upwardly from said frame-piece, substantially as described.

32. The combination, with the frame of a corn-harvester and a rearwardly and inwardly inclined cutting-knife thereon, said frame being provided with an inner longitudinal guide for the corn, of an auxiliary cutter located near the rear end of the cutting-knife over said longitudinal guide and extending upwardly therefrom, said auxiliary knife comprising stationary and movable parts operating with a shear action, substantially as described.

33. The combination, with the frame of a corn-harvester and a cutting-knife thereon, said frame being provided with a longitudinal frame-piece, which forms an inner guide for the corn, of an auxiliary cutter comprising a plate or casting attached to the said frame-piece and extending upwardly therefrom and provided with a cutting edge or edges, and a movable part or knife acting in connection with said cutting edge or edges and with an upwardly and rearwardly inclined guide m^3 , substantially as described.

34. The combination, with the frame of a corn-harvester, of a cutting-knife provided with an upwardly-extending flange at its outer edge and across its rear end, said knife having yielding connection with the machine-frame at both ends, an upright rod attached to the machine-frame, and two slotted arms attached to the said flange and engaging said rod, substantially as described.

35. The combination, with the frame of a corn-harvester and a cutting-knife supported on the frame, of a spiral conveyor conveying the butts of the cut corn inward from the knife, and a stationary transversely-arranged plate or shield located at the rear of the conveyor and knife, substantially as described.

36. The combination, with the frame of a corn-harvester having a longitudinal external frame-piece A^5 , of a cutting-knife having vertically-movable connection with the frame, a vertically-movable knife support or guard pivoted at its front end to the machine-frame and at its rear end to the knife, and an inclined guide-rod G , attached to the frame-piece A^5 and extending to the forward end of the said knife-support, substantially as described.

37. The combination, with the frame and cutting-knife of a corn-harvester, of a receptacle for cut stalks, comprising a dropping rear section and a separate tilting section at or near its front end, said tilting section being adapted to swing upwardly and forwardly at its front end and having at its said front end a series of teeth to engage the upper parts of the stalks, substantially as described.

38. The combination, with the frame and cutting-knife of a corn-harvester, of a receptacle for cut stalks, comprising a tilting section provided at its front end with a series of teeth and in front of the same with an upwardly-curved supporting-surface located in position to lift the stalks clear of the teeth when said tilting section is raised, substantially as described.

39. The combination, with the frame and cutting-knife of a corn-harvester, of a receptacle for the cut corn, provided near its forward end with a tilting section hinged at its rear end to the receptacle, and a spring applied between the forward ends of the receptacle and tilting section to receive the impact of the said section when the same is lowered, substantially as described.

40. The combination, with the main frame of a corn-harvester, of two supporting-wheels at the rear part of the frame, a wheeled supporting-frame connected with the front end of the main frame by both vertical and horizontal pivots, thills connected with the said supporting-frame, and draft connections attached to the forward end of the main frame, substantially as described.

41. The combination, with the main frame of a corn-harvester, of two supporting-wheels at the rear part of the frame, a separate wheeled supporting-frame connected with the front end of the main frame by both vertical and horizontal pivots, thills connected with the said separate supporting-frame, and draft connections attached to the forward end of the main frame, the vertical pivot being formed by cylindric pivot-rod L^3 , engaged with the main frame at a point above its lower end, and a brace rod or rods l^3 , connect-

ing the lower part of said pivot-rod with the frame, substantially as described.

42. The combination, with the main frame of a corn-harvester, of two vertically-adjustable supporting-wheels at the rear part of the frame, and a separate wheeled supporting-frame connected with the front end of the main frame by both vertical and horizontal pivots, the vertical pivot being affixed to the supporting-frame and the front end of the main frame being adjustable vertically on said vertical pivot, substantially as described.

43. The combination, with a corn-harvester, of an alarm or signaling apparatus operated by the turning of the wheels of the harvester to indicate the point at which the stalks are to be dumped, substantially as described.

44. The combination, with the corn-harvester and a supporting-wheel therefor, provided with a stud or projection, of an alarm or signaling apparatus comprising an actuating-lever operated by the said stud or projection on the wheel, a bell or gong, a

hammer acting on the gong, a revolving cam or wiper actuating the hammer, a plurality of ratchet-wheels, each having a different number of teeth, said ratchet-wheels being mounted upon a shaft which is connected with and actuates said cam, and a pawl adapted for engagement with either of said ratchet-wheels, substantially as described.

45. The combination, with the machine-frame and cutting-knife of a corn-harvester, of a receptacle for the cut corn, comprising a tilting section, which is bodily adjustable backward and forward relatively to the main part of the receptacle, substantially as described.

In testimony that I claim the foregoing as my invention I affix my signature in presence of two witnesses.

SAMUEL C. KENAGA.
